UNITED STATES PATENT OFFICE.

WALTER S. MAYER, OF PHILADELPHIA, PENNSYLVANIA, ASSIGNOR TO ELECTRIC SERVICE SUPPLIES COMPANY, OF PHILADELPHIA, PENNSYLVANIA, A CORPORATION OF PENNSYLVANIA.

SUSPENSION-CLAMP.

1,385,698.

Specification of Letters Patent. Patented July 26, 1921.

Application filed September 22, 1919. Serial No. 325,588.

To all whom it may concern:

Be it known that I, WALTER S. MAYER, a citizen of the United States, residing in the city of Philadelphia, in the county of Philadelphia and State of Pennsylvania, have invented certain Improvements in Suspension-Clamps, of which the following is a specification.

This invention relates to clamps for suspending electric trolley wires or conductors, particularly in mines, and its primary purpose is to provide a construction that is improved in simplicity, efficiency, compactness and durability, with parts of minimum number, sturdy character and positive action.

The improvements are characterized by a threaded body member having a wedging section, a sleeve threaded on the body member, and jaws fulcrumed on the sleeve and rocked thereon by the movement thereof in contact with the wedging section.

The characteristic features of the invention are embodied in the construction set out in the following description and the accompanying drawing in illustration thereof.

In the drawings, Figure 1 is a side elevation of a construction embodying the invention as commonly applied in use; Fig. 2 is a vertical sectional view taken centrally therethrough, and Fig. 3 is a sectional view taken on the line 3^x-3^x of Fig. 2.

The mechanism illustrated comprises the insulating support 1 from which depends the threaded stud 2 of usual construction.

A body nut 3 is screwed on and suspended by the stud 2, the nut being provided with the angular or wrenching top section 3^a, the downwardly tapering or coned bottom section 3^b and the intermediate threaded section 3^c.

A sleeve nut 4 is screwed on the body nut 3, being provided with the angular or wrenching section 4^a, the inwardly extending bottom lip or flange 4^c and the internal thread 4^b for engaging the thread 3^c.

Jaws 5 are provided with the segmental hubs 5^a which contain the downwardly tapering conical recesses or seats 5^b which register with the conical or wedging section 3^b and the circular notches 5^c which register with the flange 4^c. The taper of the conical section 3^b is greater than the taper of the recesses 5^b and the jaws 5 (normally separated at their tops by the cone 3^b) are

adapted to come together so that their hubs 5^a will pass through the flange 4^c when the sleeve 4 is turned so that the hubs will clear the cone.

The jaws 5 are provided with the longitudinal grooves 5^d forming the bottom lips 5^e for engaging a trolley wire or electric conductor 6 having the longitudinal grooves 6^a between which is the tongue 6^b, the lips 5^e being engaged in the grooves 6^a and the tongue 6^b disposed in the notches 5^d.

In operation, when the parts are assembled and the sleeve 4 is down, the jaws 5 are separated so that the tongue 6^b can be entered between the lips 5^e, which are brought together thereon. The sleeve 4 is now turned up on the body 3, when the flange 4^c carries the jaws upwardly and the member 3^b simultaneously spreads the hubs 5^a, the jaws being rocked thereby on the flange as a fulcrum and the lips 5^e thus pressed firmly against the tongue 6^b.

As the body nut 3 is screwed up, tight, against the insulator 1, lateral strains upon the stud 2 are prevented, and as the jaws 5 are swiveled in the revolute sleeve 4, they can be set and tightened in correct alignment or registration with the wire 6.

Having described my invention, I claim:

1. In a clamp, the combination with a body member provided with a thread and a wedging section, of a pair of jaws having parts between which said wedging section is disposed, and a sleeve threaded on said body member and engaging said jaws, whereby said jaws are rocked oppositely.

2. In a clamp, the combination with a body member provided with a thread and a conical section, of a sleeve having a thread engaging the thread of said member, and jaws fulcrumed by means of said sleeve and having said conical section disposed between them, whereby the operation of said sleeve causes said jaws to be rocked oppositely by the action of said conical member thereon.

3. In a clamp, the combination with a member provided with a tapered section, of a sleeve movable longitudinally of said member, and jaws having hubs extending into said sleeve on opposite sides of said tapered section, said sleeve and hubs having means whereby said jaws are fulcrumed and drawn toward said tapered section,

whereby said hubs are spread and said jaws are rocked oppositely to effect their clamping operation.

4. In a clamp, the combination with a stud, of a nut screwed on said stud, a sleeve screwed on said nut, and a pair of jaws fulcrumed in said sleeve on opposite sides of said nut, said nut and jaws having coacting means whereby the latter are rocked oppositely.

5. In a clamp, the combination with a stud, of a nut screwed on said stud, said nut having a conical end tapering from said stud, a sleeve threaded on said nut, said sleeve having an inturned flange, and a pair of jaws having segmental hubs extending into said sleeve, said hubs being fulcrumed on said flange and containing segmental cone recesses of smaller angularity than said conical end and in engagement with said end on opposite sides thereof.

6. A clamp for a trolley wire comprising, in combination, a member adapted for engagement with a hanger stud, two clamping members engaged with said member and capable of rotation therearound, each of said clamping members being provided with an external bearing, and a member threaded upon the first named member and adapted to engage the bearings of the clamping members to force the clamping members one

toward the other, the face of the second named member opposed to the clamping members being provided with a recess, said clamping members being provided with parts disposed within said recess.

7. A clamp for a trolley wire comprising, in combination, a suspension member provided with a socket in one end, the wall of said socket being threaded for engagement with a hanger stud, said suspension member being provided with an angular head to provide means for screwing the suspension member on the hanger stud, two clamping members engaged with the suspension member and capable of rotation therearound, each of said clamping members being provided with an external bearing, and a member threaded upon the first named member and adapted to engage the bearings of the clamping members to force the clamping members one toward the other, the face of the second named member opposed to the clamping members being provided with a recess, said clamping members being provided with parts disposed within said recess.

Signed at Philadelphia, in the county of Philadelphia and State of Pennsylvania, this 16th day of September, 1919.

WALTER S. MAYER.
